To all whom it may concern:

Be it known that I, WILLIE B. WHITE, a citizen of the United States, residing at Cleveland, in the county of Cuyahoga and State of Ohio, 5 have invented and produced a new and original Design for a Box for Speed-Wagons, of which the following is a specification, reference being had to the accompanying drawings, forming a part thereof.

10 In the accompanying drawings, Figure 1 is a plan view of a wagon-body, showing the form of my new design. Fig. 2 is a side elevation thereof.

As shown in the drawings, the leading and 15 essential features of my design consist in the parallel vertical sides 2 2, the converging end

portions 3 3, and the upwardly-inclined bottom portion 5, the said portions 3 3 and 5 terminating in a comparatively sharp point 4. What I claim is—

The design for the box of a speed-wagon, 25 substantially as shown and described.

Witness my hand to the foregoing specification this 7th day of October, 1897.
